C. W. BLOODIE.

FOLDING RULE.

APPLICATION FILED MAY 22, 1918.

1,331,951.

Patented Feb. 24, 1920.

INVENTOR
Charles W. Bloodie,
by his attorney,
J. Edward Thebaud.

UNITED STATES PATENT OFFICE.

CHARLES W. BLODIE, OF BUFFALO, NEW YORK.

FOLDING RULE.

1,331,951.

Specification of Letters Patent. Patented Feb. 24, 1920.

Application filed May 22, 1918. Serial No. 236,029.

To all whom it may concern:

Be it known that I, CHARLES W. BLODIE, a citizen of the United States, residing at Buffalo, in the county of Erie and State of New York, have invented certain new and useful Improvements in Folding Rules; and I do hereby declare the following to be a full, clear, and exact description of the same, such as will enable others skilled in the art to which it appertains to make and use the same, reference being had to the accompanying drawings, and to figures of reference marked thereon, which form part of this specification.

15 Like figures of reference refer to like parts.

This invention relates to folding rules and more particularly to the construction of the joints thereof.

20 One of the objects of this invention is to provide a slip and hold joint between contiguous members of the rule which will be positive in action in holding the contiguous members firmly in alinement, when full open or closed.

25 Another object is to provide a joint which will yield more evenly to the manual turning of the contiguous members, and at the same time be more flexible, so as not to overtax the material of the interlocking parts.

30 A further object is to provide a joint which will require less material than one of the common type, and one wherein the material is used to better advantages with respect to its elastic qualities.

35 A further object is to so form the joint parts that no pins or rivets will be required to attach the same to the members of the rule.

40 With these and other objects my invention consists in certain construction, including interlocking elastic members cut in bent alinement across the body of the joint part. Various embodiments of my invention are 45 illustrated in the drawings, the construction and functioning of the parts is explained and what I claim is set forth.

45 In the drawings, Figure 1 is a plan of a fragment of a folding rule, showing one 50 form of joint embodying my invention.

55 Fig. 2 is a side elevation of the rule and joint shown in Fig. 1.

Fig. 3 is a plan of one end of a recessed

member of a folding rule adapted to receive a part of the joint device. 55

Fig. 4 is a section taken on the line Y—Y of Fig. 3.

Fig. 5 is a plan of the rule member adjoining the member shown in Fig. 3.

Fig. 6 is a section taken on the line X—X of Fig. 3.

Fig. 7 is a plan of the joint part fitting the recessed member shown in Fig. 3.

Fig. 8 is an end elevation of the part shown in Fig. 7. 65

Fig. 9 is a plan of the joint part adapted to fit with the part shown in Figs. 7 and 8.

Fig. 10 is an end elevation of the joint part shown in Fig. 9.

Fig. 11 is a plan of a modified form of a 70 joint part to that shown in the previously mentioned figures.

Fig. 12 is an end elevation of the part shown in Fig. 11.

Fig. 13 is a plan of another form of joint 75 part differing from the others above mentioned.

Fig. 14 is an end elevation of the parts shown in Fig. 13. 80

In the figures:

Referring to Figs. 1 to 10 inclusive, the rule members 1 and 2, are pivotally joined by the rivet 3, with the washers 4, 4. Between the members 1 and 2, are the joint parts 5 and 6, fixed respectively to the members 1 and 2. The member 1 is provided with curved recesses 7 and 8, symmetrically placed about the rivet hole 9, as shown in Figs. 3, 4 and 5. The member 2 has a rivet hole 10, as shown in Fig. 5. The joint part 5 shown in Figs. 7 and 8, is of sheet metal, having a rivet hole 11, about which is symmetrically positioned the curved straps 12 and 13, each having a centrally depressed portion 14. The straps 12 and 13 are sprung beyond the plane of the plate, to provide for an elastic action when the depressions are co-fitted during the alinement of the ruled members 1 and 2. The longitudinal edges 15 and 16, are bent in at an acute 100 angle to the body 17, of the joint part 5, when the part is positioned upon the member 1 of the rule, and are thus firmly held thereon without the use of other fasteners. By making the straps 12 and 13 curved, as 105 shown in Fig. 7, they are made longer than

if they were cut straight across from the body 17, of the part 5, and are therefore, made more flexible.

The part 5 is positioned on the member 1 to have its depressed portion 14, 14, occupy the recesses 7 and 8, loosely, when the part 5 is fixed in position upon the member 1.

The joint part 6 is similar to the part 5, in the construction of the body 17^a, the 10 straps 12^a and 13^a, the depressed portions 14^a, 14^a, and is of the same size, but the edges 15^a and 16^a are turned from the body 17^a in opposite directions and at an acute angle, when attached to the ruled member 2, 15 so that when the holes 11, and 11^a of the joint parts 5 and 6, register with the holes 9 and 10 of the ruled member, the depressed portions 14, 14, of the part 5, will fit compressingly into the depressed portions 14^a, 14^a, of the part 6, when the members 1 and 2 are in line, open or shut.

The modified form of joint part shown in Figs. 11 and 12 have the strap portions 12^b and 13^b somewhat E-shaped, the bars 18 giving added flexibility and assisting to position the depressions 14^a, 14^a in spaced relation to the hole 19.

In the form shown in Figs. 13 and 14 the straps 12^c and 13^c are made angular in shape 30 to give them the extra length for the added feature of flexibility which my invention affords over the common straight strap form.

Other forms of straps which give a longer 35 strap between the longitudinal edges of the rule, may be made without departing from the spirit and scope of my invention, I

therefore do not wish to be confined to the details of construction herein shown and described, hence I claim,

1. In a folding rule having two adjoining members pivotally connected, a joint device comprising a pivotal member for holding said adjoining members together, a pair of elastic members arched transversely to 45 the face of the rule and spaced from said pivotal member, each having a projected center, each of said elastic members being fixed at its ends, and another pair of similarly arched elastic members, each having its 50 ends fixed and having depressed centers, positioned to register and lock with the said respective projections of the other pair of arched members, when said adjoining members are in line with one another.

2. In a folding rule having jointed pivoted members, a joint device forming a joint for said members, said joint device comprising two cofitting parts, a pivotal connection holding said members together, a pair of flexible elements on one of said parts equally spaced from one another about the pivotal center thereof, each of said elements having the ends thereof fixed and its center flexibly free, and a pair of flexible 65 elements on the other of said parts, positioned adjacent the aforesaid flexible elements, and slip-locking portions on said elements, positioned to be diametrically opposite one another to lock together when 70 said members are in line with one another open full or closed.

CHARLES W. BLODGIE.
